Des. 64,563

UNITED STATES PATENT OFFICE.

JOHN W. ROBISON AND MARK C. ALBRIGHT, OF MOUNT VERNON, INDIANA.

DESIGN FOR A NOVELTY PARASOL.

Application filed May 3, 1922. Serial No. 2,051. Term of patent 7 years.

To all whom it may concern:

Be it known that we, JOHN W. ROBISON and MARK C. ALBRIGHT, citizens of the United States, residing at Mount Vernon, in the county of Posey and State of Indiana, have invented a new, original, and ornamental Design for Novelty Parasols, of which the following is a specification, reference being had to the accompanying drawing, forming part thereof.

The figure is an elevation of the novelty parasol showing our new design.

We claim:

The ornamental design for a novelty parasol, as shown.

JOHN W. ROBISON.
MARK C. ALBRIGHT.
